MATCH BOOK STRUCTURE

Leo O. H. Lemke, Minneapolis, Minn.

Application December 23, 1938, Serial No. 247,381

6 Claims. (Cl. 206—29)

My invention relates to match book structures.

In use of ordinary book matches, many persons strike matches on the striking strip of a match book while the closure flap thereof is open and thus expose themselves to the danger of injury from flame issuing from the remaining matches of the book should a spark from the match being struck reach and ignite the remaining matches.

10 It is an object of my invention to provide a type of match book construction wherewith it is extremely difficult to strike a match on the striking strip of the match book other than when the closure flap of the book is in closed position.

15 A more specific object is to provide a match book having a striking strip near the free end of the closure flap and a pocket for receiving the free end of the closure flap to restrain the flap, when the same is in closed position, from sideward shifting while a match is being drawn across the striking strip.

20 These and other objects and advantages of the invention will more fully appear from the following description made in connection with the accompanying drawing, wherein like reference characters refer to the same or similar parts throughout the views, and, in which:

25 Fig. 1 is a perspective view of a match book constructed in accordance with my invention;

30 Fig. 2 is a partially broken-away side view; and

35 Fig. 3 is a sectional view taken on the line 3—3 of Fig. 2.

40 Referring to the drawing the illustrated match book structure embodying my invention includes the usual paper matches made in the form of cards from which the matches project and are separable from the common base 4a. The group of matches is provided with a cover C consisting of a generally rectangular piece of sheet material such as cardboard folded about the head ends 45 of the matches 4 so as to form a front closure flap 5 and a back portion 6 each of which extend to the base 4a. The back portion 6 may be of such length as to terminate substantially at the left-hand limit of the common base 4a as viewed in Figs. 1 and 2.

45 The closure flap 5 is provided a short distance inwardly of the free edge thereof with a strip 7 of striking material extending transversely of the flap 5. This striking material is, of course, placed on the outer side of the flap 5.

50 Means is provided for receiving the free end of the flap 5 when the same is in closed position. For this purpose a strip 8 of sheet material such as cardboard is placed on the front side of the

common base 4a and is secured thereto by suitable means such as the wire staple 9. The free end of the flap 5 may be received between the sheet of material 8 and the front side of the common base 4a.

5 Means is provided to prevent sideward shifting of the flap 5 when the free end thereof is in closed position and received over the strip 8. For this purpose the strip 8 may be bent around the side edges of the common base 8 to form retaining 10 elements 8a which will block sideward movement of the free end of the flap 5. Preferably the strip 8 is extended across the rear side of the common base 4a as at 8b so that the respective ends of the strip 8 are spaced but a small distance 15 apart. Preferably the wire staple 9 is extended through the free ends of the strip 8 through the common base 4a and finally through the portion of the strip 8 disposed at the front side of the common base 4a so as to secure all of the elements pierced by the staple 9 together. Preferably the staple 9 is applied in such a manner that the free ends of the legs thereof project above the frontmost portion of the strip 8 after which the projecting portions of the staple 9 are bent 20 or pinched as indicated in Figs. 1 and 3.

25 The flap 5 upon which the strip 7 of striking material is placed is sufficiently flexible so that the same would move sidewardly if a match were drawn along the surface of the striking material 7. Thus it would be found difficult to strike a match on the striking material 7 while the match book is open. However, the strip 8 and the portions 8a thereof form in conjunction with the upper side of the common base 4a a pocket 30 for receiving a free end of the closure flap 5 and retaining the same against sideward movement, that is, movement laterally of the match book. In use of the match book the user would be inclined to facilitate the striking of matches on the strip 7 by inserting the free end portion of the closure flap 5 in the above described pocket so as to anchor the flap 5 against sideward movement thereof. Since the usual user of a match book such as that shown would be encouraged to 35 strike matches on the strip 7 only when the closure flap is in closed position, there would be much less danger of sparks from a match being struck reaching the remaining supply of matches 40 within the book.

45 It is apparent that I have invented a type of match book structure incorporating novel features of construction tending to discourage users from striking a match on the striking strip of 50

the match book while the closure flap of the match book is open.

It will, of course, be understood that various changes may be made in the form, details, arrangement and proportions of the various parts without departing from the scope of my invention.

What is claimed is:

- 10 1. In a match book including a card of matches each projecting and separable from a common base and a cover folded about the head ends of the matches to form a back portion and a front closure flap each extending to the base, a strip of striking material placed on and extending transversely of said flap inwardly of the free edge thereof, and a strip of material extending across the front side and around the side edges of said base and secured to the rear side thereof to form in conjunction therewith a pocket for receiving the free end of said flap and retaining the same against lateral movement thereof relative to said base when a match is drawn along said strip of striking material.
- 15 2. In a match book including a card of matches each projecting and separable from a common base and a cover folded about the head ends of the matches to form a back portion and a front closure flap each extending to the base, a strip of striking material placed on and extending transversely of said flap inwardly of the free edge thereof, and a strip of material encircling said base and the free end of said back portion and secured thereto to form, in co-operation with said base, a pocket for receiving the free end of said flap whereby said encircling strip will restrain the free end of said flap from lateral movement relative to said base when a match is drawn along said strip of striking material.
- 20 3. In a match book including a card of matches each projecting and separable from a common base and a cover folded about the head ends of the matches to form a back portion and a front closure flap each extending to the base, a strip of striking material placed on and extending transversely of said flap inwardly of the free edge thereof, a strip of material encircling said base and the free end of said back portion, and an element piercing said encircling strip, said back portion and said base and arranged to secure the same to each other whereby said encircling strip forms, in co-operation with said base, a pocket wherein the free end of said flap may be received and will be restrained from lateral movement relative to said base when a match is drawn along said strip of striking material.
- 25 4. In a match book including a card of matches

each projecting and separable from a common base and a cover folded about the head ends of the matches to form a back portion and a front closure flap each extending to the base, a strip of striking material placed on and extending transversely of said flap inwardly of the free edge thereof, a strip of material encircling said base and the free end of said back portion and having free ends adjacent each other at the rear side of said back portion, and means piercing the front part of said encircling strip, said base, said back portion and the free ends of said encircling strip and arranged to secure all of the same to each other whereby the front portion of said encircling strip co-operates with said base to form a pocket therebetween wherein the free end of said flap may be received and will be restrained from lateral movement relative to said base when a match is drawn along said strip of striking material.

5. In a match book including a card of matches each projecting and separable from a common base and a cover folded about the head ends of the matches to form a back portion and a front closure flap each extending to the base, a strip of striking material placed on and extending transversely of said flap inwardly of the free edge thereof, a strip of material encircling said base and the free end of said back portion and having free ends disposed adjacent each other at the rear side of said back portion, and a staple having two legs piercing the respective free ends of said encircling strip, said back portion, said base and the front part of encircling strip and bent to overlie said front part whereby said front part co-operates with said base to form a pocket therebetween for receiving the free end of said flap and retaining the same against lateral movement thereof relative to said base when a match is drawn along said strip of striking material.

6. In a match book including a card of matches each projecting and separable from a common base and a cover folded about the head ends of the matches to form a back portion and a front closure flap each extending to the base, a strip of striking material placed on and extending transversely of said flap inwardly of the free edge thereof, and a strip of material extending across the front side of said base and rearwardly at the side edges thereof and being secured to said base to form in conjunction therewith a pocket for receiving the free end of said flap and retaining the same against appreciable lateral movement thereof relative to said base when a match is drawn along said strip of striking material.
